UNITED STATES PATENT OFFICE

2,528,577

METAL DRAWING STRIPPER

Robert T. Catlin, Stratford, and George R. Eckstein, Milford, Conn., assignors to Remington Arms Company, Inc., Bridgeport, Conn., a corporation of Delaware

Application May 5, 1949, Serial No. 91,432

9 Claims. (Cl. 205—4)

1

This invention relates to apparatus for drawing thin tubular articles, such as cartridge cases and detonator shells, and more particularly to means for stripping such drawn components from a draw punch after the punch and component have passed through a draw die.

Previous studies of this problem have resulted in various adaptations of the segmental ring stripper held in engagement with the punch and workpiece by an encircling or garter spring. Examples of such designs are shown in Patents Nos. 2,327,936, 2,345,857, and 2,369,260. Stripper of this type require an appreciable amount of space in the bottom of the die holder and, as shown in the patents, are not well adapted to retaining control of the drawn component until it has passed entirely beneath the bottom face of the die holder. In certain types of machines it is desirable to be able to transfer a drawn component into a transfer means for shifting the component to a succeeding draw or other operation. Such a transfer is facilitated if the stripper extends below the bottom face of the die block which cannot be done with the garter spring strippers.

Other disadvantages of the garter spring stripper have been the fact that they are completely disabled by broken springs, that as a result of scrap between the segments, ragged edge cups and other irregularities, they do not always strip positively, and that their working life is relatively short as a result of dulling of the working edge and various other factors.

This invention has as one of its objects the provision of stripper means adaptable to use in the transfer type machines mentioned above, which means will strip positively and at much higher operating speeds than the previously used designs.

Another object is to provide a stripper design which will have a greatly increased working life, which can be conveniently extended without reduction in efficiency by a simple sharpening operation.

Further objects are the provision of a simple one-piece design of the stripping element and a design which can be adapted to any stripping problem regardless of the size of the drawpiece involved.

It is contemplated that these objects can be best accomplished by the provision of a member comprising a spring flange and a plurality of individual low inertia collet-like fingers each of which is formed as an integral extension from the spring flange. Such a stripper may be sup-

2

ported in the bottom of the die block beneath the draw die with the passage through the fingers in alignment with the die opening. In use, the drawn component passes through the fingers, springing them outwardly and they close upon the shank of the punch. As the punch is retracted, the fingers act as compression struts between the mouth of the drawpiece and the lower face of the draw die or stripper support. Since a component of the stripping force acts to hold the end of the finger in engagement with the punch shank, there can be no slippage. Since the individually movable collet fingers have low inertia, they will respond quickly and may be used at very high press speeds.

The exact nature of the invention as well as other objects and advantages thereof will become apparent from consideration of the following specification referring to the attached drawings in which:

Figure 1 is a vertical sectional view through a die set including our improved stripper, the parts being shown in the position in which a drawn component is entering the stripper.

Figure 2 is a similar view showing the parts in the position they occupy while the punch is returning and the fingers are stripping the component from the punch.

Figure 3 is a partial elevational view of the stripper.

Figure 4 is a top plan view of the stripper.

Figure 5 is a vertical sectional view similar to Figure 2, showing a modified stripper and support therefor adapted to be used as a replacement for strippers of the type shown in the three patents above referred to.

Referring to the drawings by characters of reference, it may be seen that Figures 1 and 2 illustrate a die setup which, except for the stripper, is of the conventional form used for deep drawing tubular articles. This arrangement comprises a die cup 1, fixedly mounted on the bed of a draw press and arranged to receive, and to retain by means of the retainer plate 2, a die stack comprising a pocket die 3, a draw die 4, draw die support ring 5, and stripper 6. In accordance with usual practice, a draw punch 7 is arranged for axial reciprocation through this die stack and is suitably dimensioned to enter into a drawpiece 8, which may be fed to the pocket die by any suitable conventional means. It is the function of the punch to carry the drawpiece successively through the pocket die 3, the main draw die 4, with the usual result

of thinning and elongating the sidewall of the drawpiece, and the stripper 6. As the punch is returned to its upper position, it is the function of the stripper to remove the now tightly fitting drawpiece from the punch.

Referring particularly to Figures 3 and 4, it may be seen that the stripper 6 is of unitary construction and comprises an annular plate-like portion 9 which may be provided with a rim 10 of greater thickness. The plate-like portion 9 is separated into generally radial segments 11 by slots 12 which may terminate in holes 13 of any convenient shape and of a size such as to define between adjacent holes a portion 14 of the segment adapted to act as a spring for the entire segment. Depending from the inner edge of the segments 11 are the stripper fingers 15, each of which is an integral extension of one of the segments 11 separated from its neighbors by continuations of the slots 12. As may readily be seen from the drawings, the fingers 15, considered as a group, define a collet which is spring-urged to a minimum diameter by the spring action of the portions 14 of the segments 11. Preferably, the fingers 15 are of materially heavier cross-section than the segments 11 and hence, comparatively stiff. Internally, the collet presents a frusto-conical shape of such dimensions that a drawpiece impaled on the draw punch will force the fingers to open to permit their passage. Externally, the collet may also present a similar frusto-conical shape and should preferably be solidly backed with adequate clearance by some such construction as the frusto-conical wall 16 formed in the bottom of the die cup 1. This clearance should be so determined as to permit adequate opening of the collet for passage of the punch and any normal drawpiece while preventing the over-expansion and possible finger breakage which might otherwise result from the passage of an upside-down cup or of scrap or other fragments forced through the die with or ahead of a normal drawpiece. Preferably, the arrangement should be such that upon maximum expansion, simultaneous contact is established at corner 17 as well as on the conical surface 16.

It will be noted that the flange 9 of the stripper is received in the die cup 1 with an appreciable amount of diametrical clearance which permits a lateral shifting and self-alignment of the stripper with the entering drawpiece. The freedom of the stripper for such self-alignment is preserved, in spite of the thrust exerted on the draw dies by supporting the dies through the medium of pins 18 passing through the holes 13 of the annular flange and acting as compression struts between the bottom of the die cup and the lower draw die. Conveniently, these pins 18 may be maintained in their position by engagement in the die support ring 5 having an axial hole 20 of less diameter than the entrance to the conical portion of the stripper. The maximum permissible dimension of the hole 20 is determinable by considering a condition in which the stripper is displaced as a result of its floating movement to a maximum extent in one direction and the die support ring similarly displaced in a diametrically opposite direction. Under this extreme condition the hole 20 must be small enough to insure that no article passing through the hole can possibly strike the upper face of the stripper outside the entrance to the stripper throat, for such an impact might well fracture one or more of the segments.

To insure against scratching the drawpieces as

they pass through the stripper, the land 21 on each stripper finger should preferably be lapped to a radius of curvature substantially the same as that of the drawpieces and the edge of each finger should be well rounded. To insure that the stripper fingers will fit snugly on the punch shank and strip positively, the normal or unstressed inside diameter of the stripper lands should be slightly less than that of the punch shank. For an illustration, we may consider a stripper utilized in a draw press for caliber .22 cartridge cups having an outside diameter of substantially .224 inch which are drawn with a punch of .209 inch diameter. The stripper lands in this case should have an unstressed diameter of about .208 inch and the working surface of the lands of each finger should have a curvature corresponding to the .224 inch drawpiece.

While such conditions of unstressed diameter and radius of curvature seem at first contradictory, it is believed that a brief description of the preferred method of manufacture will make it apparent that these conditions can be met with facility. The stripper may be formed from any steel suitable for the manufacture of spring collets by conventional turning techniques in the form of a suitably dimensioned tube of somewhat greater length than the fingers and having an annular flange integral with one end. The annular flange may then be drilled at spaced intervals to separate the segment and to provide a run-out for the cutoff wheel or narrow milling cutter used to form the slots 12. Preferably, the slots will be started from near the end of the tubular section and the cuts are made toward the holes 13. If an end of the tubular portion is left without slotting, this provides a support to prevent distortion of the fingers during heat treatment and the end may be later severed by a suitable cutoff wheel. Before heat treatment, the web of the flange should be polished free of tool marks and all edges including those of the drilled holes carefully rounded. The heat treatment to be employed is, of course, determined by the material utilized, and in an illustrative case, may include oil quenching from 1450° F. followed by a 30-minute draw at 450° F. This treatment on one typical collet steel yields a spring structure having a Rockwell C hardness between 58 and 60 and has been tested for over 10,000,000 cycles of extreme flexing without failure due to fatigue or other causes.

After heat treatment and cutoff to square the end of the fingers at the right length, the stripper will be found to have substantially the desired form except that the stripper lands will define a circle .208 inch in inside diameter. Obviously, this radius of curvature is such that when a .224 inch drawpiece is forced there-through the contact with the drawpiece will be confined substantially to the edges of the fingers with resultant production of scratches which deface the product and may act as stress raisers to promote body splits. This situation can be corrected by introducing a .224 inch lap and continuing the lapping of the lands of the fingers until the lap just begins to contact at the center of each finger. With the lap removed, the point at the center of the land of each finger will fall on an inscribed circle of .208 inch while the radius of curvature of each finger will be the same as that of a drawpiece .224 inch in diameter. As a further precaution against scratches, the edges of each finger may be well rounded by passing a ribbon of polishing paper through ad-

jaçent slots and working it back and forth by successively pulling on opposite ends. Obviously, the end face of each finger should be maintained normal to the punch axis and may be renewed when worn by a simple grinding operation.

In the operation of a typical draw press employing a stripper thus constructed, the draw punch will force the drawpiece in succession through each of the dies and through the stripper. As a result of the lapping operation above referred to, substantially the entire land surface of the stripper fingers will bear on the drawpiece, so reducing the unit pressure thereon as to preclude the possibility of scratching. As the drawpiece passes beyond the fingers they spring inwardly, attempting to resume their normal inside diameter and close upon the shank of the punch. As the punch is retracted, the mouth of the drawpiece comes into engagement with the square end of one or more of the stripper fingers and the stripper is lifted with the punch until the upper face of the web comes into solid engagement with the lower face of the guard ring and all vertical play is taken out of the die stack. The stripper fingers then act as compression struts between the mouth of the drawpiece and the solidly supported die support ring with a positive stripping action and with no strain on the spring segments of the flange. Since cups seldom draw without some scalloping or other mouth irregularity, the independence of the fingers and the rigidity of each individual finger which permits any one or more to strip the workpiece without distorting the other segments is of great significance in regard to stripper life.

Other significant contributions to stripper life are the result of backing up the fingers with a suitable outside support to prevent over-expansion and, in the presence of a die support ring or other means, overlapping the entry face to prevent a distorted or upside-down drawpiece from contacting the upper face of the stripper. The full floating mounting of the stripper is also an important factor in stripper life in that it assures correct alignment and equalization of stresses for each operation.

It will be noted that the stripper fingers extend below the bottom face of the die cup and are therefore well adapted to use with a transfer type mechanism in which the drawpiece is inserted into a transfer carrier as a function of the advancing movement of the draw punch after passing through the die stack.

Figure 5 shows a modified form of our invention adapted to use as a replacement unit in certain existing presses. Since this construction will be fairly obvious from consideration of the foregoing, the description will be brief. As in the case of the modification previously discussed, the assembly illustrated comprises a die cup 25 having mounted therein by means of a retainer plate 26, a pocket die 27, a draw die 28, stripper 29, and stripper support ring 30. This form is well adapted for use with short stroke punch presses as a result of the comparatively small vertical dimension of the stripper assembly. In this case the support ring 30 provides the exterior support against over-expansion of the fingers and the guarding of the upper face is provided by the draw die 28. The amount by which the diameter of the stripper cone at the entry face exceeds that of the die land should be determined by a realistic appraisal of the conditions which may exist with a maximum tolerance diameter die cup, a minimum tolerance diameter die, and with

die and stripper displaced to a maximum extent in diametrically opposite directions. Under such extreme conditions, the die should still protect the upper face of the stripper flange. As in the case previously discussed, the die stack is supported from the bottom of the die cup by pins 31 passing through holes 32 in the stripper flange. The stripper should have sufficient lateral freedom to permit self-alignment with the drawpiece under the most extreme condition of press misalignment which may be encountered.

Although two specific forms of the invention have been illustrated in detail and some specific dimensions have been discussed, we do not consider that our invention is limited to these specific embodiments. Accordingly, reference may be had to the appended claims for the limitations properly applying to our invention.

We claim:

1. In drawing apparatus including a reciprocating punch, stripper means for removing a drawn component from said punch comprising a spring collet supported in axial alignment with said punch and having a normal inside diameter not greater than the diameter of said punch, said spring collet comprising a plurality of separate substantially rigid fingers, and a spring and supporting flange surrounding said fingers and including radially extending portions, each formed integrally with and extending radially outward from each of said fingers.

2. Stripper means as described in claim 1, said flange having a continuous outer rim and being separated into a plurality of segments extending radially inward from said continuous rim to said integral fingers.

3. In drawing apparatus including a draw die and an advancing and retracting punch, stripper means for removing a drawn component from said punch during retraction thereof comprising an annular, platelike member of spring material supported substantially coaxially with said punch, said member being radially divided into a plurality of segments each integrally united to the member adjacent the outer circumference thereof and each separated from its adjacent segments at the inner circumference of said member, and a substantially rigid finger integral with each segment and extending from the inner edge thereof in the direction of advancing movement of the punch, said fingers defining an inwardly tapering spring collet adapted to spring open to permit the punch and drawn component to pass therethrough as the punch is advancing and to close upon said punch after the drawn component has passed.

4. Stripper means as defined in claim 3, the free end of each of said fingers being formed to define a surface substantially normal to the axis of movement of said punch.

5. Stripper means as defined in claim 4, said annular member being supported at its outer circumference with limited freedom for lateral movement whereby said collet may align itself axially with said punch.

6. Stripper means as defined in claim 5, said collet being supported with limited freedom for axial movement with said punch to facilitate flexing of said annular member and a fixedly positioned stop abutment member overlying the inner circumference of said member from which said fingers extend.

7. Stripper means as defined in claim 6, and guard means circumferentially surrounding said cup spring fingers in slightly spaced relation thereto

to serve as a stop to prevent excessive displacement of the fingers.

8. Stripper means as defined in claim 7, said guard means being formed to define a frustoconical surface substantially contacting the outer surfaces of said fingers when said collet has been sprung open to a maximum safe amount.

9. Stripper means as defined in claim 8, the radial divisions of said annular member defining a plurality of openings therethrough, and draw die support means associated with said stripper and comprising columnar members passing loosely through said openings into engagement

with the lower face of the draw die to support same without impeding limited lateral and axial movement of the said annular member.
